CONVERSION OF HYDROCARBON OILS

Joseph Mason Barron, Port Arthur, Tex., assignor, by mesne assignments, to The Texas Company, New York, N. Y., a corporation of Delaware

Application February 18, 1941, Serial No. 379,463

7 Claims. (CL. 196—49)

This invention relates to a combination thermal cracking and coking and catalytic cracking process for the production of a maximum yield of high antiknock gasoline or motor fuel.

The invention contemplates a process in which a relatively light stock is subjected to catalytic cracking, the resultant hot products of the catalytic cracking combined with a higher boiling or residual stock to effect the coking thereof and fractions from the vapors produced in the coking operation subjected to thermal cracking.

In practicing the invention a crude petroleum stock is distilled to separate a residual stock from a lighter stock such as gas oil or kerosene which is adapted for catalytic cracking. This lighter stock is subjected to catalytic cracking and the resultant products of conversion directed to a coking zone. In one method of operation the topped or reduced crude is introduced into a dephlegmator to dephlegmate vapors produced in the flashing of residual constituents from the thermal cracking operation and the resultant mixture of unvaporized crude residuum and reflux condensate is passed to the coking zone for reduction to coke in contact with the hot products from the catalytic cracking operation. The evolved vapors from the coking operation are subjected to a primary dephlegmation to obtain a heavy or tarry condensate suitable for fuel oil and the dephlegmated vapors are subjected to further fractionation to separate the desired gasoline or motor fuel distillate from a higher boiling reflux condensate which is cycled to the thermal cracking zone. The products of the thermal cracking operation are separated into vapors and residue, which residue is passed to the flashing zone, while the separated vapors are combined with vapors from the coking operation for fractionation therewith. The tarry condensate obtained in the primary dephlegmation of the coke still vapors is either withdrawn to constitute a fuel oil product or is passed to a flashing zone for reduction to desired viscosity or flash test.

In a modification of the invention the residue from the thermal cracking operation instead of being passed to the flashing zone is directed to the coking zone.

In another modification contemplated by the invention the topped or reduced crude is combined with the heated stream of products from the heating coil of the thermal cracking operation and the combined products are subjected to cracking in a reaction zone, and in this operation the residue obtained in separating the

products of the thermal cracking may either be passed to the coking zone for reduction to coke or delivered to the flashing zone for the production of fuel oil.

5 For the purpose of more fully disclosing the invention reference is now had to the accompanying drawing which is a flow diagram illustrating drawing which is a flow diagram illustrating apparatus adapted for the practice of the invention.

10 In the apparatus illustrated a crude oil stock, such as crude oil or topped crude, is directed by a pump 10 to a heating coil 11, heated by heat exchange with hot product from the system or otherwise, and is passed thence to a tower 12 wherein separation of vapors from residue takes place and wherein the separated vapors are subjected to fractionation. The residue is withdrawn through a line 13 in which is a pump 14. Condensate fractions, such as gas oil and kerosene constituents, suitable for catalytic cracking are collected in a tray 15 while any lighter fractions which it is not desired to subject to catalytic cracking are passed overhead to a condenser coil 16 and receiving drum 17.

15 The condensate from tray 15 of tower 12 is withdrawn through a line 18 and directed by a pump 19 to a heating coil 20 disposed in a furnace 21 and the heated oil is passed to a catalytic cracking chamber 22 containing a bed of catalyst material. Ordinarily, a plurality of catalyst chambers are used so that the catalyst may from time to time be revivified or regenerated without disturbing the continuity of the complete combination process.

20 The catalyst consists advantageously of a synthetic silica-alumina type of catalyst. Various acid-treated and metal-substituted clays such as the Super-Filtrols and acid-treated and metal-substituted natural or artificial zeolites, such as the artificial zeolite known as Doucill may be employed. Various metals such as uranium, molybdenum, manganese, lead, zinc, zirconium, nickel and the like, may be substituted in the clays or zeolites. Likewise, the combination of certain acid-treated active clays of the character of Filtrol, together with added proportions of alumina or silica or both may be employed. Alumina alone may be used under certain conditions. The synthetic alumina catalysts can be improved by the addition of other constituents such as zirconium oxide or molybdenum oxide.

25 The thermal cracking portion of the system includes a heating coil 23 disposed in a furnace

24 having a transfer line 25 extending to a reaction chamber 26 which has a discharge line 27 extending to a second reaction or separating chamber 28. Residue from chamber 28 is withdrawn through a line 29 to a flash tower 32 wherein the residue is flash distilled under reduced pressure. Separation of vapors from residue takes place in the tower 32 and the residue is withdrawn through a line 33 while the separated vapors pass into the upper sections of the tower for fractionation.

Crude residuum is directed by the pump 14 through the line 13 to an upper section of the flash tower 32 to dephlegmate the vapors therein, a resultant mixture of reflux condensate and unvaporized residuum collecting on a tray 34. A pump 35 conducts the crude residuum mixture from tray 34 through a line 36 to a coking drum 37. The hot products from the catalytic cracking zone 22 are discharged through a line 38 communicating with line 36 so that hot products are mixed with the crude residuum mixture so as to be converted to coke in the coking chamber 37.

In a modification of the invention the crude residuum from the crude stripping tower instead of being introduced into the flash tower is directed through a branch line 13a of the line 13 and combined directly with the hot products from the catalytic cracking zone for coking in the coking chamber 37.

The vapors from the coking drum pass through a vapor line 39 to a fractionating tower 40. The vapors from the coking drum preferably pass to a primary dephlegmating section 40A of the tower wherein the vapors from the coking operation are subjected to a primary dephlegmation to form a heavy or tarry condensate. The dephlegmating section 40A may be refluxed with gas oil. A portion of the bottoms withdrawn from dephlegmator 40A may be advantageously recycled through the dephlegmator in order to provide a flow of liquid therein to prevent coking. Bottoms from dephlegmator 40A may be conducted through a line 41 and thence through line 29 to the flash tower. Vapors uncondensed in the dephlegmating section 40A pass upwardly to a fractionating section 40B for further fractionation, the resultant reflux condensate being collected on a tray 42.

Vapors from the chamber 28 pass through a vapor line 43 to the tower 40, preferably entering the tower at a point above the trapout tray 42, and the combined vapors from the chamber 28 and from the dephlegmating section 40A are subjected to fractionation in fractionating section 40B. Reflux condensate is withdrawn from tray 42 by a pump 44 and directed through a line 45 to the heating coil 23. The overhead vapors from tower 40 pass to a condenser 46 and the distillate is collected in a receiving drum or gas separator 47.

The overhead distillate from the flash tower 32 passes to a condenser coil 48 and the distillate is collected in a receiving drum 49 or gas separator. The flash distillate is withdrawn through a line 50. This distillate consists essentially of thermally cracked constituents and it may with advantage be directed to the catalytic cracking zone. A pump 51 having an intake line communicating with line 50 and having a discharge line 52 is provided for directing a portion or all of the flash distillate to the heating coil 20 of the catalytic cracking unit. If desired, a portion or all of the flash distillate may be refluxed in either or both of the fractionating sections 40A 75

and 40B of tower 40 and in this way flashed constituents will be included in the cycle condensate passing to the thermal cracking zone.

In a modification of the invention the residue 5 withdrawn from chamber 28, instead of being directed to the flash tower, may be directed through a branch line 53 of the line 29 and combined with hot products from the catalytic cracking zone for coking.

- 10 In another modification of the invention the crude residuum from the crude stripping tower passing through line 13 may be directed through a branch line 54 and combined with the hot products passing from the heating coil 23 and the 15 mixture subjected to cracking in the reaction chambers, and in this method of operation the residue separating out in chamber 28 may either be passed through the line 31 to the flash tower or through line 53 to the coking chamber.
- 20 In practicing the invention the crude oil stock is distilled and fractionated into the fractions desired. A fraction suitable for catalytic cracking is heated in the heating coil 20 to a temperature sufficient to maintain the desired temperature in the catalyst case 22. Thus, the oil in transit through the coil 20 is vaporized and is heated sufficiently to maintain cracking temperatures of the order of 850° F. to 1050° F. and preferably temperatures of 910° F. to 1000° F. in the 30 catalyst case 22. The topped or reduced crude, as it comes from the stripping tower at temperatures of the order of 600° F. to 750° F., is combined directly with the hot products discharging from the catalyst case and the mixture is passed 35 to the coking drum for coking, or the topped or reduced crude may be introduced into the dephlegmator of the flashing unit and the resultant mixture of heavy reflux condensate and unvaporized residue is combined with the hot products 40 from the catalyst case for coking in the coking chamber. Cycle condensate from the fractionator 40 is subjected to thermal cracking in the heating coil 23 and reaction chambers 26 and 28 under the usual temperatures suitable for thermal 45 cracking and under superatmospheric pressures, usually in excess of 100 lbs. and preferably of the order of 400 to 600 lbs. The so-called low-liquid-level or no-liquid-level conditions are preferably maintained in the reaction chambers 26 and 28, the residue being rapidly withdrawn from the chamber 28 so as to prevent the accumulation of liquid. Distillate comprising a mixture of gasoline constituents formed in the catalytic cracking, thermal cracking and coking is collected in the receiver 17.
- 55 The cracked residue withdrawn from chamber 28 is normally passed to the flashing tower for flash distillation to produce a fuel oil product of desired flash and viscosity, or to produce a high viscosity product adapted for the preparation of a fuel oil product by cutting back with a suitable high flash condensate stock. While it is within the purview of the invention to combine the residue from the thermal cracking operation with the hot products from the catalytic cracking operation to effect coking, it is generally preferable to utilize the thermally cracked residue for the production of fuel oil, while reducing the topped or reduced crude to coke by being admixed with the catalytically cracked products. The cracked residue, particularly when it consists essentially of polymers produced by cracking, is better adapted for fuel oil than the crude oil residue, since the cracked residue is characterized by having a higher specific gravity and a higher calo-

rific value for a given viscosity than the un-cracked residual stock, and furthermore, the coking of the topped or reduced crude will ordinarily produce greater yields of gasoline and intermediate stock adapted for further cracking into gasoline with relatively less gas production than is the case in coking the cracked residue. There is, consequently, a particular advantage in accomplishing the reduction of the topped or reduced crude to coke by means of the hot products from the catalytic cracking operation while reserving the residue from the thermal cracking operation for the production of fuel oil. The heavy tarry condensate which is produced in the primary dephlegmation of the vapors from the coking drum is also well adapted for the production of fuel oil and may be withdrawn as a separate product or passed to the flashing zone together with the residue from the thermal cracking operation.

In the operation in which the crude residuum is passed through line 54 to be combined with the hot products from the cycle condensate heating or cracking coil 23 the crude residue may be withdrawn from the crude stripping tower at temperatures of 600° F. to 750° F. and combined with the hot products from the heating coil which ordinarily leave the coil at temperatures of the order of 900° F.-1000° F. In this operation the residue withdrawn from the reaction chamber 28 may be converted to coke by being combined with the hot products from the catalytic cracking operation, or this residue may be passed to the flashing zone in which case the products from the catalytic cracking zone may be reduced to coke in the coking zone without the addition thereto of the thermally cracked residue.

In an example of the invention virgin gas oil of 30 A. P. I. gravity is charged to the heating coil of the catalytic cracking unit at a rate of 150 barrels per hour. The oil is heated to a temperature of 1000° F. and passed into the catalyst case which is maintained under a pressure of 100 lbs. per square inch. Topped crude of 26 A. P. I. gravity is preheated by heat exchange with flashed vapors, with vapors from the crude fractionator and with vapors from the pressure fractionator of the thermal cracking unit and it is further heated by furnace heat to a temperature of about 650° F. and is then introduced into the dephlegmating section of the flash tower. The resultant mixture of reflux condensate and unvaporized crude residuum is combined with the hot products discharging from the catalyst case and subjected to coking in the coking drum. In the thermal cracking operation the cycle condensate is heated to a temperature of 950° F. in the heating coil and the reaction chambers are maintained under 400 lbs. pressure with a temperature of 910° F. in the first reaction chamber, while the residue is discharged from the second reaction chamber at a temperature of 850° F. This residue is passed to the flashing chamber in which a pressure of about 5 to 15 lbs. is maintained. Pressures approximating 100 lbs. are maintained in the coking drum and in the pressure fractionator in which the vapors from the thermal cracking and coking operations are fractionated. Vapors leave the coking drum at temperatures of about 840° F. to 850° F. and vapors pass from the second reaction chamber at a temperature of 850° F. to 870° F. to the fractionator.

While I have described a particular embodiment of my invention for purposes of illustration, it should be understood that various modifi-

cations and adaptations thereof which will be obvious to one skilled in the art, may be made within the spirit of the invention as set forth in the appended claims.

5 I claim:

1. In the conversion of hydrocarbon oils the process that comprises separately distilling crude petroleum to separate residual constituents from lighter components, subjecting such straight-run 10 lighter components to catalytic cracking, combining residual constituents from the crude petroleum with hot products from the catalytic cracking operation and converting the admixed products to coke in a coking zone, subjecting the 15 evolved vapors from the coking zone to a primary dephlegmation to form a tarry condensate adapted for fuel oil, passing the dephlegmated vapors to a fractionating zone wherein the vapors are fractionated to separate a reflux condensate 20 from lighter products, directing said reflux condensate to a thermal cracking zone wherein the oil is subjected to cracking conditions of temperature and pressure, separating the resultant cracked products into vapors and residue and 25 combining the separated vapors with vapors from the coking operation, after said primary dephlegmation thereof, for fractionation in said fractionating zone.
2. In the conversion of hydrocarbon oils the 30 method of treating a crude petroleum residual charging stock and a straight-run condensate stock that comprises subjecting the condensate stock to catalytic cracking, combining the residual stock with hot products from the catalytic 35 cracking operation and converting the admixed products to coke in a coking zone, subjecting the evolved vapors from the coking zone to a primary dephlegmation to form a tarry condensate, passing the dephlegmated vapors to a fractionating 40 zone wherein the vapors are fractionated to separate a reflux condensate from lighter products, directing said reflux condensate to a thermal cracking zone wherein the oil is subjected to cracking conditions of temperature and pressure, 45 separating the resultant cracked products into vapors and residue, and combining the separated vapors with vapors from the coking operation, after said primary dephlegmation thereof, for fractionation in said fractionating zone.
3. In the conversion of hydrocarbon oils the 50 process that comprises distilling crude petroleum to separate a residue from a lighter fraction, subjecting the lighter fraction to catalytic cracking, dephlegmating vapors from a flashing zone with 55 said residue to form a resultant mixture of reflux condensate and unvaporized residue, combining said mixture with hot products from the catalytic cracking operation and converting the admixed products to coke in a coking zone, subjecting the 60 evolved vapors from the coking zone to a primary dephlegmation to form a tarry condensate, passing the dephlegmated vapors to a fractionating zone wherein the vapors are fractionated to 65 separate a reflux condensate from lighter products, directing said reflux condensate to a thermal cracking zone wherein the oil is subjected to cracking conditions of temperature and pressure, separating the resultant cracked products into vapors and residue, passing the separated vapors to 70 said fractionating zone and directing the separated residue and said tarry condensate to said flashing zone.
4. In the conversion of hydrocarbon oils the 75 method of treating a residual stock and a condensate stock that comprises subjecting the con-

densate stock to catalytic cracking, dephlegmating vapors from a flashing zone with the residual stock to form a resultant mixture of reflux condensate and unvaporized residue, combining said mixture with hot products from the catalytic cracking operation and converting the admixed products to coke in a coking zone, subjecting the evolved vapors from the coking zone to a primary dephlegmation to form a tarry condensate, passing the dephlegmated vapors to a fractionating zone wherein the vapors are fractionated to separate a reflux condensate from lighter products, directing said reflux condensate to a thermal cracking zone wherein the oil is subjected to cracking conditions of temperature and pressure, separating the resultant cracked products into vapors and residue, passing the separated vapors to said fractionating zone and directing the separated residue and said tarry condensate to said flashing zone.

5. In the conversion of hydrocarbon oils the method of treating a residual stock and a condensate stock that comprises subjecting the condensate stock to catalytic cracking in a catalytic cracking zone, dephlegmating vapors from a flashing zone with the residual stock to form a resultant mixture of reflux condensate and unvaporized residue, subjecting the dephlegmated vapors to condensation, directing resultant condensate to the catalytic cracking zone, combining the residual stock mixture, obtained in dephlegmating the flashed vapors, with hot products from the catalytic cracking operation and converting the admixed products to coke in a coking zone, subjecting the evolved vapors from the coking zone to a primary dephlegmation to form a tarry condensate, passing the dephlegmated vapors to a fractionating zone wherein the vapors are fractionated to separate a reflux condensate from lighter products, directing said reflux condensate to a thermal cracking zone wherein the oil is subjected to cracking conditions of temperature and pressure, separating the resultant cracked products into vapors and residue, passing the separated vapors to said fractionating zone and directing the residue separated from the thermally cracked products to said flashing zone.

6. In the conversion of hydrocarbon oils the

method of treating a residual stock and a condensate stock that comprises subjecting the condensate stock to catalytic cracking, dephlegmating vapors from a flashing zone with the residual stock to form a resultant mixture of reflux condensate and unvaporized residue, combining said mixture with hot products from the catalytic cracking operation and converting the admixed products to coke in a coking zone, subjecting the evolved vapors from the coking zone to a primary dephlegmation to form a tarry condensate, directing the tarry condensate to said flashing zone, passing the dephlegmated vapors to a fractionating zone wherein the vapors are fractionated to

5 separate a reflux condensate from lighter products, directing said reflux condensate to a thermal cracking zone wherein the oil is subjected to cracking conditions of temperature and pressure, separating the resultant cracked products into 10 vapors and residue, passing the separated vapors to said fractionating zone and passing the separated residue to said coking zone for conversion to coke therein.

15 7. In the conversion of hydrocarbon oils the process that comprises distilling crude petroleum to separate a residue from a lighter fraction, subjecting the lighter fraction to catalytic cracking, passing cycle condensate to a heating zone wherein it is heated to a cracking temperature, combining said residue with the heated products from 20 said heating zone and subjecting the commingled products in a thermal reaction zone to cracking temperature under superatmospheric pressure to effect cracking, separating the resultant 25 cracked products of the thermal cracking into vapors and residue, passing the separated vapors to a fractionating zone wherein the vapors are fractionated to separate a reflux condensate from lighter products, directing said reflux condensate to 30 said heating zone as said cycle condensate, combining the resultant hot products from the catalytic cracking operation with the residue separated from the thermally cracked products and converting the admixed products to coke in a 35 coking zone, subjecting the evolved vapors from the coking zone to a primary dephlegmation to form a tarry condensate and passing the dephlegmated vapors to said fractionating zone.

JOSEPH MASON BARRON.
